[57] **CLAIM**

The ornamental design for a horse saddle pad with speakers and pockets for carrying a portable cassette or disc player, as shown and described.

DESCRIPTION

FIG. 1 is a front view of a horse saddle pad with speakers and pockets for carrying a portable cassette or disc player showing my new design;

FIG. 2 is a right side view thereof;

FIG. 3 is a left side view thereof;

FIG. 4 is a top view thereof;

FIG. 5 is a bottom view thereof; and,

FIG. 6 is a rear view thereof.

The broken lines in FIG. 6 are used to represent stitching.
